Primary Examiner — Sheryl Lane*Assistant Examiner* — Nicole C Shiflet(74) *Attorney, Agent, or Firm* — Sterne, Kessler, Goldstein & Fox P.L.L.C.(57) **CLAIM**

The ornamental design for a wearable device with graphical user interface, as shown and described.

DESCRIPTION

FIG. 1 is a front view of a wearable device with graphical user interface showing the claimed design; and, FIG. 2 shows an environmental wearable device on which the design of FIG. 1 may be used.

The outermost broken lines showing a display screen in FIG. 1 and the broken lines showing a display screen and wearable device in FIG. 2 form no part of the claimed design. The remaining broken lines showing portions of the graphical user interface form no part of the claimed design.
